UNITED STATES PATENT OFFICE.

PERLEY C. WELLMAN, OF EMPORIA, KANSAS.

MACHINE FOR APPLYING BOX-STAYS.

1,097,112.

Specification of Letters Patent.

Patented May 19, 1914.

Application filed May 6, 1913. Serial No. 765,889.

To all whom it may concern:

Be it known that I, PERLEY C. WELLMAN, a citizen of the United States, residing at Emporia, in the county of Lyon and State 5 of Kansas, have invented certain new and useful Improvements in Machines for Applying Box-Stays, of which the following is a specification.

The purpose of this invention has been to 10 devise a special machine designed particularly for use in applying wire or metal stays and clips to boxes of light construction, such as are commonly used at the present time for the transportation of berries, fruit, etc.

15 The machine hereinafter described is advantageous in facilitating the application of peculiarly shaped stays to the lower portion of the box or receptacle in such a manner that the stay forms not only a brace or reinforcement for the bottom of the box but its 20 ends are clamped and secured to the sides of the receptacle in a very effective manner to accomplish the desired results.

A further object of the invention has been 25 to design a machine of the type mentioned which is exceedingly simple in construction and readily susceptible of operation by a foot lever or equivalent manually operable means, the latter being capable of actuating 30 levers which force clamping jaws into co-operation with a stationary head, all of which will be clear upon reference to the detailed specification of parts found herein- 35 after and to the accompanying drawings, in which—

Figure 1 is a perspective view of a machine embodying the invention, the manual operating means omitted. Fig. 2 is a longitudinal section of the machine bringing out 40 clearly the manner in which the foot lever is connected with the levers that actuate the jaws, and showing a stay in the process of being applied to a box, the latter being broken away. Fig. 3 is a transverse section 45 through the upper parts of the device. Fig. 4 is a fragmentary view illustrating the manner in which the invention is employed in applying clips to the box.

In the drawings, A designates a base plate 50 which is screwed or otherwise secured upon a bed that may consist of a table, bench, or similar support B. Suitable fastenings C, such as screws are employed to connect the plate A with the support B. Intermediate 55 its ends, the base plate A has an upwardly projecting head 1, the lower portion of

which is provided with a longitudinal opening 2. Jaws 3 are mounted to slide lengthwise of the plate A and said jaws are provided with shanks 3' that are received and operate in the opening 2 of the head 1. A spiral spring 4 in said opening 2 is interposed between the inner adjacent ends of the shanks 3' of said jaws 3 and said spring being expansive in tension, tends to force the 60 jaws 3 apart in opposite directions relative to each other. The jaws 3, by reason of their disposition in respect to the head 1 are situated adjacent to the opposite ends of the head and are movable toward and from 65 said ends.

Pivoted upon the base plate A are the actuating levers 5. Each lever 5 is pivoted intermediate its ends at 5' and is formed with what may be termed a cam extremity 5'', which operates in sliding engagement with the outer side of the adjacent jaw 3. In other words, each jaw 3 is practically located between one end of the head 1 and the adjacent cam extremity 5'' of a 75 lever 5.

Operating means for the jaws 3 is provided in the form of a foot lever 6 pivoted to the floor of the room in which the machine may be situated. Said foot lever 6 is 80 connected by a rod, cable, or similar member 7 with a link 8. The link 8 in turn is connected with small links 9 which are attached to the adjacent ends of the actuating levers 5, the latter ends being located beneath the 85 plate A. Suitable slots are formed in the plate A through which the levers 5 pass, as may be readily observed upon reference to Fig. 2 of the drawings.

Describing the operation of the invention, 90 Fig. 2 illustrates the machine with the parts arranged as when applying a wire stay to the bottom portion of a common form of berry box. It may be observed that the opposite ends of the head 1 really form die 95 faces coöperating with the jaws 3 and said faces are grooved as shown at 1^a, the inner faces of the jaws 3 being similarly grooved as shown at 3^a and the upper surface of the head 1 having a longitudinal groove shown 100 at 1^b. The groove 1^b is provided to form a seat for the body of the stay designated at 10, whereas the grooves 1^a and 3^a are supplied in order to insure that the ends of the stay 10 will be held in proper position during 105 the operation of clamping said ends in engagement with the sides of the box 11. In

other words, the grooves 1^a and 3^a counteract any tendency of the stay 10 to slip out of the space between the jaws 3 and the die faces at the ends of the head.

5 Assuming that the parts are arranged substantially in the positions shown in Fig. 2, it is observed that by depressing the foot lever 6, the lower inner ends of the levers 5 are pulled downwardly and the upper cam 10 extremities 5" are caused to have a slight oscillatory movement in impinging with the outer surfaces of the jaws 3 in such a way as to force said jaws under great pressure toward the head 1. The ends of the stay 10 15 are in this manner effectively clamped into firm engagement with the sides of the box 11, while the intermediate or body portion of the stay is also in this manner pressed tightly against the bottom of the box so as 20 to brace and reinforce the latter in an adequate manner against sagging, which has become a great defect in boxes of this special construction. It will be noted that the long 25 arms of the levers 5 are lowermost, the cam extremities 5" constituting the short arms, this detail affording powerful action of the jaws 3 on the ends of the stay to clip the latter on the sides of the box, as will be readily apparent.

30 In Fig. 4, the invention is illustrated in the operation of applying a clip of U-form to a box for the purpose of connecting lapped-over portions of the material from which the receptacle is made. It is obvious 35 that, in applying such a clip, designated at 12, the action of only a single jaw 3 is required, whereas, in securing the stay 10 to the box, the simultaneous action of the jaws 3 is necessary.

40 Having thus described the invention, what is claimed as new is:

1. In a machine of the class described, the combination of a base plate, a head projecting upwardly from said plate and having 45 one end thereof constituting a die face, said head being also provided with an opening therein, a jaw slidably mounted on the base plate and having a shank mounted to move in said opening of the head so that 50 the jaw may coöperate with the die face of the latter, a lever pivoted between its ends to the base plate and having a cam extremity impinging the outer side of the jaw to force the latter toward the head, and 55 means for actuating said lever.

2. In a machine of the class described, the combination of a base plate, a head projecting upwardly from said plate and having one end thereof constituting a die face, 60 said head being also provided with an opening therein, a jaw slidably mounted on the base plate and having a shank mounted to

move in said opening of the head so that the jaw may coöperate with the die face of the latter, a lever pivoted between its ends to 65 the base plate and having a cam extremity impinging the outer side of the jaw to force the latter toward the head, means for actuating said lever, and a spring housed in said opening of the head and normally tending to force the jaw outwardly into a position spaced from the die face aforesaid. 70

3. In a machine of the class described, the combination of a base plate having a head projecting therefrom, a pair of jaws 75 slidably mounted on said base plate and movable toward and from opposite portions of the head, levers having cam extremities engaging the outer sides of the jaws to force the same toward the head, means for simultaneously operating said levers, the head being provided with a longitudinal opening and the jaws having shanks operating in said opening, and a coiled spring interposed between the adjacent ends of the 80 shanks and tending to force the same outwardly from the head.

4. In a machine of the class described, the combination of a head having die faces at its opposite ends, a pair of jaws 85 slidable toward and from the die faces of the head, levers having end portions thereof engaging the jaws at their outer sides, means for actuating said levers to force the jaws toward the head, said head being provided 90 with a longitudinal opening and the jaws having shanks freely slidable in said opening, and spring means tending to force said jaws apart in directions away from the head. 100

5. In a machine of the class described, the combination of a base plate, a head projecting upwardly therefrom and having at its lower portion a longitudinal opening therethrough, jaws comprising shanks sliding 105 freely in said opening and on the base plate, a spiral spring interposed between the inner ends of the shanks and tending to force the jaws outwardly away from opposite ends of the head, levers passing through the base 110 plate and having cam extremities engaging the outer sides of the jaws above the plate, and the lower ends arranged beneath the plate, and a link connected with the lower ends of the levers to simultaneously operate 115 the same, the inner sides of the jaws and co-operating ends of the head being grooved for the purpose described.

In testimony whereof I affix my signature in presence of two witnesses.

PERLEY C. WELLMAN.
